PHOTO IDENTIFICATION FOR CHECKS

Bernard L. Goldwater, Brooklyn, N. Y.

Application January 15, 1945, Serial No. 572,879

1 Claim. (Cl. 283—7)

1

This invention relates to new and useful improvements in photo identification for checks.

More specifically, the invention proposes a new and improved check which is characterized by having an identification photograph printed on it. This identification photograph may be of the payee, or the signee.

Still further the invention proposes to arrange the photograph in several possible ways, and yet embody the characteristics of this invention.

Another object of the invention is to associate a maximum amount indicator around the photograph.

Still further the invention proposes several modified forms which embody the main features of the invention.

Another object of the invention resides in the construction of a new and improved check as mentioned which may be used just as conveniently as present day checks and embodies improved and desirable features so as to make the new check desirable. It is also proposed to so arrange the construction of the check that it may be manufactured and used substantially as cheap as present day checks.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure:

Fig. 1 is a perspective view of a new and improved check embodying this invention.

Fig. 2 is a fragmentary sectional view taken on the line 2—2 of Fig. 1.

Fig. 3 is a front view of another check embodying this invention but constructed in accordance with a modified form.

Fig. 4 is a fragmentary sectional view taken on the line 4—4 of Fig. 3.

Fig. 5 is another plan view of a check constructed in accordance with another form of this invention but illustrated without its sticker.

Fig. 6 is another plan view of the check shown in Fig. 5 with its sticker.

Fig. 7 is a fragmentary enlarged sectional view taken on the line 7—7 of Fig. 6.

Fig. 8 is a perspective view of the sticker used in Figs. 6 and 7.

The new and improved photo identification for checks in accordance with that form of the invention illustrated in Figs. 1 and 2 includes a check 10 having an identification photograph

2

11 printed near the upper left hand corner. This photograph may be that of the payee, or of the signee. If the photograph is of the payee, the particular type of check is only practical for checks to employees where each week, or each short period of time a new check is issued. The bank would then have no trouble in identifying the employee presenting the check for payment. In this case a note might be placed above said photograph to the effect that the likeness is that of the payee. Should the photograph be that of the signee of the check, its value lies in the publicity given to the signee, so that the signee would become known to large groups of people, also to prevent forgery.

The invention also proposes the provision of a maximum amount indicator 12 arranged around the photograph 11. This indicator is in the nature of a plurality of numbers printed around the photograph 11 and each number being bounded by perforated areas 14. Beneath the photograph 11 there is a legend 15 which reads "Not more than." The intention is that one of the numbers be removed, when the check is issued, and the check will not be good for a larger amount than the one number which has been removed.

In Figs. 3 and 4 a modified form of the invention has been disclosed which is very similar to the prior form distinguishing merely in the fact that a transparent protecting sticker 16 is pasted over and across the photograph 11 and over and across the maximum amount indicator 12. With this arrangement the particular number indicating the maximum amount of the check need not be removed, but instead it has been folded back and has been pasted down by the sticker 16. The folded back section is indicated by reference numeral 17.

The protective sticker 16 not only protects the photograph but also makes it harder to tamper with the maximum amount indicator of the check.

It is to be understood that the checks may be perforated by and the use of a pencil or any perforating device for recording the maximum cash value of the check.

In Figs. 5 to 8 inclusive still another form of the invention has been disclosed which is very similar to the prior form of the invention, but distinguishes in a number of ways. In this check, the identification photo 20 is of a circular design contrasted with the prior design which was square. The maximum amount indicator is imprinted around the periphery of the photograph

20. For each check, a disc-like sticker 22 is provided which has an opaque peripheral section 23 interrupted by a small transparent area 24. The center of the sticker 22 is transparent. The sticker is provided with a suitable adhesive 25 upon its back face by which it may be pasted down upon the check. The sticker 22 is also provided with a legend 26 reading "Not more than."

After the check has been written out, the sticker 22 is pasted down over the photograph so that the photograph may be seen through the transparent area. It is positioned so that the transparent peripheral section 24 exposes one of the numbers of the maximum amount indicator 21.

In other respects this form of the invention is identical to the prior forms and identical parts may be recognized by the same reference numerals.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention what I claim as new, and desire to secure by United States Letters Patent is:

5 A check having an identification photograph printed thereon, and a maximum amount indicator arranged around said photograph, and comprising a plurality of numbers which are bounded by a perforated area making it easy for one of the numbers to be partially or completely removed, and a transparent sticker secured over said photograph and over said maximum amount indicator.
